TAKEDOWN MECHANISM FOR FIREARMS

David Emerson, New Haven, Conn., assignor to
 Olin Industries, Inc., New Haven, Conn., a corporation of Delaware

Application February 16, 1949, Serial No. 76,681

9 Claims. (Cl. 42—75)

1

The present invention relates in general to firearms and more especially to a firearm of the takedown type, that is to say, a firearm in which the barrel-unit and frame-unit of the firearm are readily separable one from the other, for convenience in packing, shipping and carrying.

An object of the invention is to provide a firearm with superior takedown-means for readily attaching the barrel-unit to the frame-unit of the firearm and for detaching the barrel-unit from the frame-unit.

A further object of the invention is to provide a takedown firearm with superior takedown-means of durable and dependable construction and of relative simplicity and economy of manufacture.

A still further object of the invention is to provide a superior takedown-means for firearms embodying an improved detent for releasably locking the takedown-means against inadvertent release.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken side elevation of a firearm embodying the improved takedown mechanism of this invention;

Fig. 2 is an enlarged broken side elevation of a portion of the firearm shown in Fig. 1, the fore-end being shown in section to illustrate the principal elements of the improved takedown mechanism;

Fig. 3 is a further enlargement of a fragmentary portion of the firearm shown in Fig. 2, the enlargement being a side elevation in section of the fore-end and fragmentary sectional elevations of the barrel-locking lug and the forward end of the tubular magazine;

Fig. 4 is an end elevation in section of the fore-end and tubular magazine on line 4—4 of Fig. 3;

Fig. 5 is a perspective view of the connector-bolt of the takedown mechanism;

Fig. 6 is an enlarged perspective view of the end-plug of the tubular magazine showing the guide-recess in the front face thereof for accommodating the improved guillotine detent; and

Fig. 7 is a perspective view of the guillotine

2

detent of the improved takedown mechanism of this invention.

The particular takedown firearm herein chosen for illustrating the invention may be considered to include two principal units separable one from the other to enable the firearms to be more conveniently packed, shipped or carried. The one unit of the firearm may, for convenience of description, be designated as the "frame-unit" and comprises, in the main, the receiver 10 having a buttstock 11 secured at the rear end thereof and a tubular magazine 12 secured to the forward end thereof, the tubular magazine 12 being in communication at its rear end with the breech-bolt chamber of the receiver.

The complementary "barrel-unit" comprises, in the main, a barrel 13 adapted to be detachably secured in any suitable manner, such as by means of continuous or interrupted threaded engagement, within an aperture in the front face 20 of the receiver; and a barrel-locking lug 14. The latter is a substantially L-shaped member having a long leg-portion 15 fixedly secured to the underside of the barrel 13 longitudinally thereof and substantially intermediate its opposite ends; and an apertured short leg 16 extending at substantially right angles to the long leg 15 of the locking-lug and projecting downwardly from the underside of the barrel, for the purpose hereinafter described, the aperture of the short leg 16 opening upon the front and rear faces of the short leg 16 and being provided with internal threads 17.

As shown in Figs. 3 and 4, the fore-end 18 of the firearm is provided with a relatively-deep vertical recess 19 intersecting the top side thereof and extending from the rear end thereof forwardly throughout a major portion of its length, the recess 19 being substantially U-shaped in cross section and having a transverse dimension corresponding substantially to the diameter of the tubular magazine 12 for accommodating the latter. The forward end of the recess 19 intersects a relatively-shallow clearance-aperture 20 which also intersects the top side of the fore-end and is adapted to provide clearance for the short leg 16 of the barrel-locking lug 14 when the fore-end is assembled on the barrel-unit. The front wall of the aforesaid clearance-aperture 20 of the fore-end is intersected by the rear end of a counterbore 21 concentric to a longitudinal aperture 22 which extends forwardly through the fore-end to the front end thereof for accommodating the connector-bolt of the takedown mechanism, the forward end of the aforesaid aper-

ture 22 and the front end of the fore-end being reinforced by a grommet 23.

Referring again to the tubular magazine 12 of the firearm, the forward end of the tubular magazine is provided with a magazine-plug 24 which, as shown in Fig. 6 is a substantially cylindrical member adapted to be secured in the forward end of the tubular magazine 12 by a transverse pin 25 which extends through a transverse aperture 26 of the plug and is engaged at its opposite ends in axially-aligned apertures in the forward end of the tubular magazine. As shown in Fig. 4, the pin 25 is provided with an annular groove 27 intermediate its opposite ends and extending substantially transversely of its longitudinal axis.

The front end of the magazine-plug is formed with a U-shaped guide-recess 28, the upper end of which opens upon the top side or face of the plug. Further, the guide-recess 28 lies in a vertical plane substantially parallel to but spaced rearwardly of the front face of the magazine-plug thereby to provide the guide-recess 28 with a front wall 29, the latter being characterized by a vertical substantially U-shaped slot 30 which also opens upon the top side of the plug, whereby the front wall 29 of the guide-recess constitutes, in effect, a substantially U-shaped flange 31 extending inwardly from the corresponding substantially vertical side walls 32-32 and the curved bottom wall 33 of the guide-recess.

The back wall 34 of the guide-recess comprises a substantially planar surface in spaced-parallel relationship to its front wall 29 and provided with an aperture 35 in the vertical plane of but slightly above the longitudinal axis of the plug and terminating in a blind end 37 immediately forwardly of the rear end of the plug. As shown in Figs. 3, 4 and 6, the bottom wall of the hole 35 intersects the top wall of the plug-aperture 26 substantially intermediate its opposite ends such that when the magazine-plug is secured in the forward end of the tubular magazine by the pin 25, the annular groove 27 of the latter will be opposite the intersection of the bottom wall of the hole 35 with the top wall of the transverse aperture 26. Further, it will be noted that the longitudinal axis of the drilled hole 35 is substantially in alignment both with the longitudinal axis of the internally-threaded aperture 17 of the barrel-lug and the longitudinal axis of the aperture 22, extending forwardly through the fore-end.

Referring again to Fig. 6, formed at the lowest point in the bottom wall 33 of the guide-recess 28 and coextensive with the vertical axis thereof, is an aperture 38 constituting a well for accommodating a coil-spring 39 which is adapted to support the guillotine detent of the takedown mechanism in the guide-recess 28 of the magazine-plug. Referring especially to Fig. 7, the guillotine detent, indicated generally at 40, comprises a substantially rectangular plate approximately equal in thickness to the distance between the flanged front wall 29 and the rear wall 34 of the guide-recess 28, whereby the guillotine detent is adapted to be slidably held therein for substantially vertical movement only, the detent being guided for vertical movement in the guide-recess 28 by engagement of the sides 41-41 of the detent with the respective side walls 32-32 of the guide-recess. The upper edge 42 of the guillotine detent is curved as shown in Fig. 4, to correspond to the curvature of the upper surface of the magazine-plug and the inner wall of the

tubular magazine, the upper edge 42 of the guillotine detent constituting stop-means adapted to engage squarely against the inner wall of the tubular magazine to limit the upward movement of the guillotine detent in the guide-recess of the magazine-plug. The bottom edge 43 of the guillotine detent is curved to correspond to the curvature of the bottom wall 33 of the guide-recess and is intersected at substantially the center of its arc of curvature by a rectangular slot 44 extending upwardly from the bottom of the detent. When the guillotine detent is assembled in the guide-recess of the magazine-plug, its rectangular slot 44 is located immediately above the spring 39 in the spring-retaining aperture 38 of the magazine-plug such that the upper end of the spring 39 is adapted to abut against the upper edge 45 of the slot 44, thereby to resiliently support and urge the guillotine detent upwardly in the guide-recess of the magazine-plug.

Formed at substantially the geometric center of the guillotine detent is a generally rectangularly shaped aperture 46, the over-all dimensions of which are such that the connector-bolt of the takedown mechanism may pass freely therethrough, as shown in Fig. 4. The bottom edge 47 of the aperture 46 is provided with a plurality of upwardly projecting teeth 48 which are intermediate its opposite ends and which extend transversely of the bottom edge 47 of the aperture, that is to say, in the direction of the longitudinal axis of the magazine-plug, for lockingly engaging the connector-rod of the takedown mechanism in adjusted position, in the manner hereinafter described.

The connector-rod of the takedown mechanism is indicated generally at 49 and, as shown in Fig. 5, comprises an elongated cylindrical bar having an enlarged, cylindrical head 50 at its forward end provided with a slot 51 in its front face for receiving a tool or coin for turning the connector-rod; and an aperture 52 extending transversely through the side of the cylindrical head for accommodating a wire nail or similar instrument when greater leverage is required for turning the connector-rod.

The opposite end of the connector-rod is of reduced diameter and is provided with a beveled edge as indicated at 53, so that when assembling the rod in the longitudinal aperture of the fore-end and the axially-aligned aperture of the magazine-plug, as hereinafter described, the beveled edge 53 of the rod will cammingly engage against the toothed edge of the resiliently supported guillotine detent and displace the latter downwardly in its guide-recess of the magazine-plug against the resistance of the spring 39, thereby to enable the rear end of the connector-rod to pass through the aperture of the guillotine detent into the longitudinal aperture of the magazine-plug. In this connection, the reduced diameter of the rear end of the rod is of such size that the latter is adapted to fit nicely in the aperture of the magazine-plug, to firmly support the forward end of the tubular magazine; and to engage in the annular groove 27 of the fastening-pin 25 to lock the latter against movement in the transverse aperture of the magazine-plug.

Immediately forwardly of the beveled end of the rod, the periphery of the latter is fluted in a manner to provide a plurality of spaced-parallel teeth 54 extending longitudinally of the rod, the dimensions and shape of the longitudinal teeth 54 corresponding substantially to the teeth 48 of the guillotine detent so as to mesh readily there-

with as the connector-rod is pushed through the aperture of the guillotine detent, in the manner hereinabove described.

To insure engagement of the teeth 54 of the connector-rod with the teeth 48 of the guillotine detent, the teeth of the rod are elongated sufficiently normally to extend an appreciable distance on opposite sides respectively of the detent.

The connector-rod 49 forwardly of the elongated teeth 54, is formed with external screw threads 55 adapted to threadedly engage in the internally-threaded aperture 17 of the short leg 16 of the barrel-lug, the threaded portion 55 of the rod extending normally an appreciable distance on opposite sides respectively of the short leg 16. Formed on the rod between the forward end of its externally-threaded portion 55 and its smooth shank-portion 56, is an annular groove 57 adapted to accommodate a snap-ring 58, the outside diameter of which is greater than the inside diameter of the longitudinal aperture 22 of the fore-end so that when the connector-rod is disconnected from the barrel-lug and the fore-end removed from the underside of the barrel, the connector-rod will be held from dropping out of the fore-end. That is to say, the connector-rod is adapted to be assembled in the fore-end preparatory to assembling the fore-end on the barrel-unit by pushing the rod, reduced end first, through the longitudinal aperture thereof and then engaging the snap-ring 58 in the annular groove 57 to retain the connector-rod in the fore-end.

The assembly and operation of the elements of the improved takedown mechanism may be described briefly as follows. The guillotine detent 40 and its spring 39 are first assembled in the guide-recess 28 of the magazine-plug 24, whereupon the latter is inserted in the forward end of the tubular magazine and secured therein by means of the transverse pin 25. The fore-end 18, including the connector-rod 49 assembled therein as hereinabove described, is then mounted on the underside of the barrel to enclose the tubular magazine, the reduced rear end of the connector-rod being thrust through the internally-threaded aperture 17 of the short leg 16 of the barrel-lug and the aperture 46 of the guillotine detent into the longitudinal aperture 35 of the magazine-plug. The externally-threaded portion 55 of the connector-rod is then threadedly engaged in the aperture 17 of the barrel-lug by applying a coin or other tool in the kerfed head of the connector-rod and rotating the rod in a clockwise direction. Continued rotation of the connector-rod will thereupon advance the longitudinal teeth 54 of the rod into engagement with the teeth 48 of the guillotine detent. Since the latter is resiliently mounted for vertical sliding movement only in the guide-recess of the magazine-plug, the camming action effected by rotational engagement of the longitudinal teeth of the connector-rod with the teeth of the detent displaces the detent downwardly positively against the resistance of its spring, the force of which moves the detent upwardly again as each longitudinal tooth of the rod wipes over a tooth of the detent. Thus, as the connector-rod is threaded into the barrel-lug, the guillotine detent undergoes a short-stroke reciprocating movement in the guide-recess of the magazine-plug. It will be appreciated also that as the connector-rod is threaded into the barrel-lug, engagement of the head of the connector-rod with the grommet 23 in the front face of the fore-end draws the fore-end 18 rearwardly relative to the barrel-unit so that the rear

end of the fore-end is seated firmly against the forward end of the receiver. Additional rotation of the connector-rod thereupon tends to pull the barrel-unit forwardly relative to the frame-unit, the effect being to take up any backlash in the threaded connection of the barrel with the receiver.

Once the fore-end and barrel have been pulled up tightly in assembled relationship on the receiver, the connector-rod is effectively held from inadvertent rotation in a direction to loosen the fore-end and barrel by resilient engagement of the teeth 48 of the guillotine detent with the teeth 54 of the connector-rod, disengagement of which may be effected only by overcoming the resistance of the detent-spring.

The improved detent mechanism of this invention is thus characterized by a resiliently mounted guillotine detent slidable in the magazine-plug for releasably locking the connector-rod of the takedown mechanism in adjusted position, the fewness of parts and the simplicity of manufacture and assembly providing a superior and economical takedown mechanism for firearms.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a takedown firearm, including in combination: a barrel-unit; a frame-unit including a tubular magazine; a fore-end constructed and arranged to be assembled on the underside of said barrel-unit and said tubular magazine; and takedown mechanism for securing said fore-end and barrel-unit to said frame-unit and for preventing any relative movement between such parts, said takedown mechanism comprising connector-means mounted in said fore-end and arranged to be threaded into said barrel-unit, and detent-means carried by said tubular magazine and arranged to engage said connector-means to hold the latter in threaded engagement with said barrel-unit.
2. A takedown firearm as defined in claim 1, which further includes resilient-means associated with said detent-means for normally urging said detent-means into engagement with said connector-means thereby to releasably hold the latter in threaded engagement with said barrel-unit.
3. In a takedown firearm, including in combination: a barrel-unit; a frame-unit including a tubular magazine; a fore-end constructed and arranged to be assembled on the underside of said barrel-unit and said tubular magazine; and takedown mechanism for securing said fore-end and barrel-unit to said frame-unit and for preventing any relative movement between such parts, said takedown mechanism comprising connector-means having teeth thereon, said connector-means being mounted in said fore-end and arranged to be threaded into said barrel-unit, and detent-means carried by said tubular magazine, said detent-means having teeth arranged to engage the teeth of said connector-means thereby to lock the latter in threaded engagement with said barrel-unit.
4. A takedown firearm as defined in claim 3, which further includes resilient-means associ-

ated with said detent-means for normally urging the teeth of said detent-means into locking engagement with the teeth of said connector-means thereby to releasably hold the latter in threaded engagement with said barrel-unit.

5. In a takedown firearm, including in combination: a barrel-unit; a frame-unit including a tubular magazine having an end-plug; a fore-end constructed and arranged to be assembled on the underside of said barrel-unit and said tubular magazine; and takedown mechanism for securing said fore-end and barrel-unit to said frame-unit and for preventing any relative movement between such parts, said takedown mechanism comprising connector-means mounted in said fore-end and arranged to be threaded into said barrel-unit, detent-means, means to slidably support said detent-means in the end-plug of said tubular magazine, and resilient-means mounted in the end-plug of said tubular magazine, said resilient-means being arranged normally to urge and resiliently hold said detent-means in engagement with said connector-means thereby to releasably hold the latter in threaded engagement with said barrel-unit.

6. In a takedown firearm, including in combination: a barrel-unit; a frame-unit including a tubular magazine having an end-plug provided with an aperture; a fore-end constructed and arranged to be assembled on the underside of said barrel-unit and said tubular magazine; and takedown mechanism for securing said fore-end and barrel-unit to said frame-unit and for preventing any relative movement between such parts, said takedown mechanism comprising connector-means mounted in said fore-end, said connector-means being arranged to engage in the aperture of said end-plug and to be threaded into said barrel-unit, detent-means carried by said tubular magazine, said detent-means having an aperture therethrough to receive said connector-means, and resilient-means associated with said detent-means for normally urging said detent-means into engagement with said connector-means thereby to releasably hold the latter in threaded engagement with said barrel-unit.

7. In a takedown firearm, including in combination: a barrel-unit; a frame-unit including a tubular magazine having an end-plug provided with a guide-recess; a fore-end constructed and arranged to be assembled on the underside of said barrel-unit and said tubular magazine; and takedown mechanism comprising connector-means mounted in said fore-end and arranged to be threaded into said barrel-unit, detent-means slidably mounted in the guide-recess of the end-plug of said tubular magazine, and resilient-means mounted in the guide-recess of said end-plug, said resilient-means being arranged normally to urge and resiliently hold said detent-means in engagement with said connector-means thereby to releasably hold the latter in threaded engagement with said barrel-unit.

8. In a takedown firearm, including in combination: a barrel-unit; a frame-unit including a

tubular magazine having an end-plug provided with a guide-recess in the face thereof; a fore-end constructed and arranged to be assembled on the underside of said barrel-unit and said tubular magazine; takedown mechanism for securing said fore-end and barrel-unit to said frame-unit, said takedown mechanism comprising connector-means having teeth thereon, said connector-means being mounted in said fore-end and arranged to be threaded into said barrel-unit, detent-means slidably mounted for substantially vertical movement only in the guide-recess in the front face of said end-plug, said detent-means having teeth arranged to engage the teeth of said connector-means; and a detent-spring mounted in the guide-recess of said end-plug, said detent-spring being arranged to engage the underside of said detent-means normally to resiliently hold the teeth of said detent-means in engagement with the teeth of said connector-means thereby to releasably hold the latter in threaded engagement with said barrel-unit.

9. In a takedown firearm, including in combination: a barrel-unit; a frame-unit including a tubular magazine having an end-plug provided with a guide-recess in its front face and an aperture extending substantially at right angles thereto; a fore-end constructed and arranged to be assembled on the underside of said barrel-unit and said tubular magazine; and takedown mechanism for securing said fore-end and barrel-unit to said frame-unit and for preventing any relative movement between such parts, said takedown mechanism comprising a connector-rod having teeth thereon and external threads, said connector-rod being mounted in said fore-end and arranged to engage in the aperture of said end-plug and to be threaded into said barrel-unit, detent-means slidably mounted for substantially vertical movement only in the guide-recess of said end-plug, said detent-means having an aperture centrally thereof to receive said connector-rod, and teeth on one edge of said aperture to engage the teeth of said connector-rod, and a detent-spring mounted in the bottom of said guide-recess, said detent-spring being arranged to engage the underside of said detent-means normally to resiliently hold the teeth of said detent-means in engagement with the teeth of said connector-rod thereby to releasably hold the latter in threaded engagement with said barrel-unit.
